DESIGN FOR A BOLERO SWEATER

Martin H. Scheinwald, New York, N. Y.

Application December 22, 1937, Serial No. 73,794

Term of patent 3½ years

To all whom it may concern:

Be it known that I, Martin H. Scheinwald, a citizen of the United States of America, residing in city of New York, county of New York, and State of New York, have invented a new, original, and ornamental Design for a Bolero Sweater, of which the following is a specification, reference being had to the accompanying drawing, forming part thereof.

Fig. 1 is a front view of a bolero sweater showing my new design.

Fig. 2 is a rear view thereof.

My design is characterized by the specific striped vestee in combination with the bolero embodying a high collar and wing-like revers as shown.

I claim:

The ornamental design for a bolero sweater, substantially as shown and described.

MARTIN H. SCHEINWALD,
